UNITED STATES PATENT OFFICE

FRED ISAACSON AND WALTER M. CAUGHLAN, OF DENVER, COLORADO

SWITCH-POINT LOCK

Application filed April 14, 1930. Serial No. 444,263.

This invention relates to new and useful improvements in electrically operated railroad switches and has for the primary object, the provision of means for holding or locking the switch point in either of its positions, thereby obviating the possibility of the de-railing of car trucks caused by the switch point not remaining fully in either of the operative positions.

Another object of this invention is the provision of a device which may be easily and quickly applied to the switch operating means and which will maintain the switch point in either of its positions after being thrown from one position to another.

A further object of this invention is the provision of a switch point lock of the above stated character, which will be simple, durable and efficient, and which may be manufactured and sold at a comparatively low cost.

With these and other objects in view as will become more apparent as the description proceeds, the invention consists in certain novel features of construction, combination and arrangement of parts as will be herein-after more fully described and claimed.

For a complete understanding of our invention, reference is to be had to the following description and accompanying drawings, in which:

Figure 1 is a side elevation illustrating an electrical operating means for a railroad switch with our invention applied thereto.

Figure 2 is a plan view illustrating a switch point lock constructed in accordance with our invention.

Figure 3 is a fragmentary side elevation illustrating the same.

Figure 4 is a detail sectional view taken on the line 4—4 of Figure 2.

Referring in detail to the drawings, the numeral 1 indicates a casing having located therein electromagnets 2 and 3 having their cores pivotally connected to the ends of an

operating arm 4 by links 5 and the arm 4 is pivotally mounted in the casing 1 intermediate the ends thereof and has an operating rod or link 6 pivoted thereto and adjacent one end. The rod or link 6 extends outwardly of the casing 1 for connection in the usual manner with a switch point or a railroad switch (not shown). The foregoing description relates to a well known construction of electrical operating means for a railroad switch and to which our invention is applied. It is to be understood that the magnets 2 and 3 are energized in the usual way by a car approaching the switch and the energizing of one magnet will move the switch into one of its positions while the energization of the other magnet will move the switch point to its other position. In use it has been found that there is a possibility of the switch point not fully reaching or maintaining its operative positions, consequently causing de-railment of the car trucks and to obviate this danger our invention is employed.

A supporting plate 7 is arranged in the casing 1 and carries a bolt or pivot 8 on which is mounted a bell crank lever 9. The arm 10 of the bell crank lever 9 has one end of a coil spring 11 secured thereto while the other end of the coil spring is secured to the casing as shown at 12 for the purpose of holding the bell crank lever in either of its positions as shown by full lines and dotted lines in Figure 2. An adjustable stop 13 is mounted in a bracket 14 carried by the plate 7 and is engaged by the arm 15 of the bell crank lever 9 when in one of its positions or in the position shown in full lines in Figure 2.

An adjustable link 16 has ball and socket connections with one end of the arm 4 and with the arm 15 of the bell crank lever 9. The link 16 besides pivotally connecting the bell crank lever to the end of the arm 4 also will permit a slight yielding movement of the bell crank lever relative to the arm 4.

The link 16 includes tubular portions or elements 17 and 18 adjustably connected by a screw threaded rod 19 and the latter is bent slightly intermediate its ends as shown in Figure 4 to dispose the elements 17 and 18 at a slight angle relative to each other. Suitable locking nuts 20 are threaded on the rod 19 and engage with the ends of the elements 17 to lock said rod to said elements in any of their various adjusted positions relative to each other. The elements 17 and 18 have their outer ends closed by removable bearing blocks 21 which cooperate with bearing elements 22 in receiving balls or spheres 23 on the ends of shanks 24 formed integrally with screw threaded attaching portions 25. The elements 17 and 18 are provided with slots 26 to permit swinging motion of the shanks and the attaching portions 25 relative to the elements 17 and 18. The bearing portions 22 are yieldably supported in engagement with the balls or spheres by coil springs 27. The bearing elements 22 being yieldably supported will take up wear between the balls and spheres and their respective bearing elements. The attaching portion 25 is connected to the bell crank lever and the arm 4 as heretofore described.

In operation, when the switch point (not shown) has been moved to either of its positions by the operation of the electromagnets, the bell crank lever 9 will swing beyond dead center and the tension of the spring will retain the switch point fully in either of its operative positions consequently obviating any possibility of the switch point becoming positioned so as to cause de-railment of car trucks when passing over the switch.

While we have shown and described the preferred embodiment of our invention, it will be understood that minor changes in construction, combination and arrangement of parts may be made without departing from the spirit and scope of the invention as claimed.

Having thus described our invention, what we claim is:

1. In combination with a switch point operating mechanism having an operating arm, a pivotally mounted bell crank lever, tension means connected to one end of the bell crank lever, a link pivotally connected to the other end of the bell crank lever and to the arm and capable of adjustment as to length and adapted to permit a limited movement of the bell crank lever relative to said arm.

2. In combination with an electrically operating switch point mechanism having an arm, a pivotally mounted bell crank lever, tension means connected to one end of the bell crank lever, and an adjustable link having universal connections with the end of the arm and the other end of the bell crank lever.

3. In combination with a switch point operating mechanism having an arm, a pivotally

mounted bell crank lever, tension means connected to one end of the bell crank lever, a link connected to the arm and to the bell crank lever and including a pair of tubular members, a rod adjustably secured to said tubular members and bent intermediate its ends, bearing blocks adjustably mounted in said members, and balls received by said bearing blocks and having connections with the bell crank lever and said arm.

In testimony whereof we affix our signatures.

FRED ISAACSON.
WALTER M. CAUGHLAN.
